[57] CLAIM

The ornamental design for a cycle exerciser, as shown and described.

DESCRIPTION

FIG. 1 is a perspective view of a cycle exerciser showing our new design;

FIG. 2 is a side elevational view thereof, the opposite side being substantially a mirror image thereof;

FIG. 3 is a top plan view thereof;

FIG. 4 is a front elevational view thereof; and

FIG. 5 is a rear elevational view thereof.

FIG. 1.

FIG. 2.***FIG. 3.***FIG. 5.

FIG. 4.
